UNITED STATES PATENT OFFICE.

HUGH GAIR, OF OAKPARK, ILLINOIS.

MATCH.

SPECIFICATION forming part of Letters Patent No. 746,321, dated December 8, 1903.

Application filed February 18, 1903. Serial No. 143,922. (No model.)

To all whom it may concern:

Be it known that I, HUGH GAIR, a resident of Oakpark, in the county of Cook and State of Illinois, have invented certain new and useful Improvements in Matches, of which the following is a specification.

This invention relates to improvements in matches, and pertains more particularly to improvements in matches of the safety type or those in which the ignition compound will ignite only when rubbed upon a special composition. The invention is, however, capable of embodiment in other types of matches.

The salient object of the invention is to provide a match which embodies in itself a complete device whereby a light may be secured; to provide a construction of the character referred to which has a detachable portion which is so formed that the detachment thereof does not shorten or substantially destroy the convenience and burning capacity of the match; to provide a construction which may be economically and readily manufactured by machinery, and in general to provide a simple and improved device of the character referred to.

To the above ends the invention consists in the matters hereinafter described, and more particularly pointed out in the appended claims, and will be readily understood from the following description by reference to the accompanying drawings, forming a part thereof, and in which—

Figure 1 is a side elevation of a complete match embodying my invention. Fig. 2 is a plan view of the butt-end portion of a match enlarged. Fig. 3 is a cross-sectional view taken approximately on line 3-3 of Fig. 2. Figs. 4, 5, and 6 are views corresponding, respectively, to Figs. 1, 2, and 3 of a modified construction.

Referring to the drawings, 1 designates as a whole the body or match-splint, which in the most approved form is rectangular in cross-section and may be of the ordinary dimensions or desirably slightly larger than those most commonly used at present.

2 designates the ignition-head, which may be applied in any of the well-known ways, and in the most approved form of the invention consists of a composition which will ignite

only when applied to a special friction composition.

3 designates a detachable section of the match-body, and 4 a coating of abrasive material or chemical composition adapted to ignite the match when the head of the latter is rubbed thereon. In the preferred embodiment (shown in Figs. 1 to 3, inclusive) the detachable section 3 is a wedge-shaped piece 55 which is made readily detachable by forming oblique longitudinally-extending cuts 5 in the laterally-opposite sides of the match-body, near one end thereof, the ends of the cuts 5 at the wider end of the detachable section being preferably arranged to terminate a short distance from the end of the match-body, as indicated at 6. These cuts are arranged in the same plane and extend into the body of the match a distance slightly less than one-half the width of the match, so as to leave an intervening uncut web portion 7 (see Fig. 3) in addition to the uncut butt-end portion 8, thereby leaving the detachable portion 3 reliably united with the match-body, but capable of being detached therefrom readily by twisting the detachable portion relatively to the main body of the match. The coating 4 desirably covers the principal part of the broader exposed side of the detachable section, as shown clearly in the drawings.

In use the user first detaches the section and then applies it to the head of the match with a combined drawing and rubbing motion, and so ignites the match, or the section may be detached and the match-body reversed and the head applied thereto and rubbed upon the detached section in the usual manner. It will be noted that the removal of the detached section does not shorten the match, but, on the contrary, leaves it of its full original length, although tapering at its butt-end. The detached section is, moreover, of sufficient length and breadth to enable it to be conveniently applied to the match-head as described.

In Figs. 4 to 6 the detachable section 3' is made by means of L-shaped cuts 9, arranged in laterally opposite relation and extending inwardly in substantially the manner described in connection with Figs. 1 to 3. In this instance, however, the transversely-disposed portions of the cuts 3" desirably meet

and may therefore be made by a knife which is arranged to cut inwardly from the top surface of the splint to a depth sufficient to intersect the plane of the longitudinal cuts 9. 5 In this instance said longitudinal cuts 9 are shown as extending entirely to the butt-end of the splint, and in order to prevent the detachable section from being broken off too easily the butt-ends of the splint are provided 10 with a coating 10, of glue or analogous reinforcing material.

Obviously either of these forms may be embodied in the ordinary friction-matches—*i. e.*, those provided with an ignition compound 15 which will ignite when applied to any suitable friction-surface; but it is equally obvious that the utility of the invention is greatest when embodied in a "safety-match." It will be further obvious that the precise form 20 of the detachable section is not essential so long as it be such that when detached it does not substantially shorten the match-body and at the same time is of sufficient length to be conveniently handled and applied to the 25 match-head. I do not, therefore, limit myself to the precise details of construction shown.

I claim as my invention—

1. A match provided with a detachable section forming a part of the original splint and separable therefrom along longitudinal division-cuts whereby the original length of the splint remains substantially unimpaired after the section has been detached, said sections being provided respectively with an igniting 35 and a friction substance at points normally remote from each other.

2. A match-body cut or scored to separate longitudinally from the butt-end to a point intermediate its length, the longer section being provided at one end with an ignitable head, and the other section with a coating of friction material.

3. A match-body of rectangular form in cross-section provided at its butt-end with 45 cuts arranged in the same plane and extending obliquely from points near the butt-end and near one side of the match-body to points intermediate the length of the splint and at the opposite side of the match-body, the combined depth of said cuts being less than the thickness of the match-body.

HUGH GAIR.
